Primary Examiner — Robert M Spear*Assistant Examiner* — John Voytek(57) CLAIM

The ornamental design for a textile including pattern, as shown and described.

DESCRIPTION

FIG. 1 is a top plan view of a textile including a pattern showing my new design; and,

FIG. 2 is a top plan view of a second embodiment of a textile including a pattern, showing my new design.

The bottom plan views of FIGS. 1 and 2 are flat and unornamented, thus are not illustrated. The dot-dash lines in FIGS. 1 and 2, which define the bounds of the claimed design, form no part thereof.
